OIL BURNER

Charles E. Glebe, Rankin, Tex.

Application July 21, 1932, Serial No. 623,867

3 Claims. (Cl. 158—63)

The device forming the subject matter of this application is an oil burner, and one object of the invention is to provide novel means whereby the oil will be atomized before it passes to the vaporizer. Another object of the invention is to provide novel means whereby both the atomizer and the vaporizer will be heated from the burner. A further object of the invention is to supply novel means whereby the oil or other liquid fuel will be changed into gas before it is delivered to the burner.

It is within the province of the disclosure to improve generally and to enhance the utility of devices of that type to which the invention applies.

With the above and other objects in view, which will appear as the description proceeds, the invention resides in the combination and arrangement of parts and in the details of constructions hereinafter described and claimed, it being understood that changes in the precise embodiment of the invention herein disclosed, may be made within the scope of what is claimed, without departing from the spirit of the invention.

In the accompanying drawing:

Fig. 1 shows in top plan, a device constructed in accordance with the invention;

Fig. 2 is a vertical section;

Fig. 3 is a side elevation showing the cap of the vaporizer;

Fig. 4 is a side elevation showing the base of the vaporizer.

The device forming the subject matter of this application preferably is made of metal throughout. It comprises an air inlet member 1, including a vertical tubular body 2, having a lateral air intake 3.

The numeral 4 designates a burner, which is horizontally disposed, the burner including a head 5, which, preferably, is of somewhat greater diameter than the body 2 of the air inlet member 1. The head 5 is supported on the upper end of the body 2 of the air inlet member 1, and has a sleeve 6 which extends downwardly into the body 2 of the air inlet member, to hold the burner 4, which is removable, in place against lateral sliding. In the upper surface of the head 5 of the burner 4 there is an outer annular groove 7, with which communicates a downwardly extended oil drain pipe 10. The head 5 of the burner is provided with an inner annular groove 8, the inner wall of which is defined by an upstanding neck 9, which extends upwardly above the remaining portions of the head 5.

The numeral 10 designates a hollow vaporizer, including a base 11, having a concaved recess 12 in its bottom, the recess 12 being disposed immediately above the neck 9, in vertically spaced relation thereto. The base 11 of the vaporizer 10 comprises an upwardly thickened central portion 14, the convexity of which is more pronounced than the concavity of the recess 12, so that the said central portion 14 is thickest at its center, that is, in the axis of the neck 9. The base 11 of the vaporizer 10 comprises an outwardly extended rim 15 having depending legs 16, supporting the base of the vaporizer from the neck 9, in spaced relation thereto. The legs 16 have downwardly extended projections 17 engaged within the neck 9 to hold the vaporizer 10 against lateral movement, the vaporizer being removably mounted on the burner.

The vaporizer 10 includes a hollow cap 18 resting at its lower edge, removably, on the rim 15 of the base 11 of the vaporizer, there being openings or notches 48 in the lower edge of the cap 18, immediately adjacent to the rim 15 of the base 11 of the vaporizer. The cap 18 of the vaporizer is provided with downwardly extended fingers 19, which engaging the rim 15 of the base 11 of the vaporizer, hold the cap 18 in place, removably, against lateral movement.

To the top of the cap 18 of the vaporizer is attached a vertically extended, laterally prolonged pipe 20, connected to the inner end of a hollow atomizer 21, the inlet pipe for the oil being marked by the numeral 22, and being connected to the outer end of the atomizer 21. On its bottom, the atomizer 21 has upwardly extended ribs 23, extended entirely across the atomizer from side to side. These ribs 23 increase progressively in height from the outer end of the atomizer to the inner end of the atomizer, and are disposed in the path of the fuel entering the atomizer by way of the pipe 22. The surfaces of the ribs 23 which are adjacent to the inlet pipe 22 are inclined away from the inlet pipe and are disposed at an acute angle to the flow line of the fuel, the said surfaces being marked by the numeral 24. The inner surfaces of the ribs 23 are marked by the numeral 25 and are disposed approximately at right angles to the flow-line of the fuel proceeding from the inlet pipe 22.

In practical operation, the oil enters the atomizer 21 by way of the pipe 22. The oil impinges against the inclined surfaces 24 of the ribs 23, and is carried upwardly as the oil advances toward the pipe 20. The result is that the oil is thoroughly disintegrated in the atomizer 21. It

is to be observed that the atomizer 21 is located above the grooves 8 and 7 of the burner, and the oil in the atomizer 21 is heated to a considerable degree, the oil, often, being turned partially into gas, within the atomizer 21.

The oil, and such portions of it as may have been turned into gas, proceeds through the pipe 20 into the vaporizer 10. The upwardly convexed portion 14 of the base 11 of the vaporizer carries the oil laterally, and the oil flows out of the notches 48 of the cap 18, into the grooves 8 and 7. In the vaporizer 10, the oil is turned almost completely into gas, and burns at the notches or openings 48, air being supplied through the neck 9. If any oil, not turned into gas, is received in the grooves 8 and 7, the oil, of course, burns there, and the grooves 7 and 8 are of peculiar utility for receiving a priming charge, at the starting of the burner. Owing to the great thickness of the central portion 14 of the base 11 of the vaporizer, the base of the vaporizer will not be cooled to any appreciable extent by the air that comes upwardly through the neck 9 and is received in the recess 12. The recess 12 serves to carry the air laterally and deliver it around the periphery of the base 11, and, owing to the provision of the recess 12, the air is directed downwardly toward the grooves 8 and 7. Any surplus oil received in the groove 7, at the priming of the burner, or at any other time, is carried back by the pipe 70 to any suitable receptacle provided for that purpose. Owing to the small diameter of the pipe 70, there is not air enough in it to support combustion, and the flame does not work back, in practice, through the pipe 70 to the place where the surplus oil, if any, is stored.

Having thus described the invention, what is claimed is:

1. In a device of the class described, a vertical tubular air inlet member, a starting burner on the upper end of the air inlet member and having an upstanding tubular neck communicating with the air inlet member, the burner being provided in its upper surface with continuous inner and outer annular grooves disposed about the neck, a vaporizer located above the neck, spacing means

separating the vaporizer from the neck and supporting the vaporizer on the neck, the vaporizer having outlets about its periphery and located above the inner groove, to discharge thereinto, the outer groove forming an overflow receptacle for the inner groove, a drainage outlet for the outer groove, and means for supplying fuel downwardly into the top of the vaporizer. 5

2. In a device of the class described, a vertical tubular air inlet member, a starting burner on the upper end of the air inlet member and having an upstanding tubular neck communicating with the air inlet member, the burner being provided in its upper surface with an annular groove disposed about the neck, a vaporizer located above the neck, spacing means separating the vaporizer from the neck and supporting the vaporizer on the neck, the vaporizer having outlets about its periphery and located above the groove, to discharge thereinto, an atomizer offset to one side of the axis of the vaporizer and located above the vaporizer, in close relation thereto, the atomizer extending across the groove from a point outwardly of the groove to a point inwardly of the outlets of the vaporizer, means for supplying fuel to the atomizer, and a conduit leading from the atomizer to the top of the vaporizer.

3. In a device of the class described, a starting burner, a vaporizer supported above the starting burner, an atomizer supported above the burner, a connection between one end of the atomizer and the vaporizer, and an oil inlet at the opposite end of the atomizer, the atomizer being provided on its bottom with upstanding ribs which are disposed transversely to the flow-line from the inlet to the connection, the connection being joined to the atomizer at a greater height than the inlet, the ribs having substantially vertical surfaces and having inclined surfaces which are presented toward the inlet, the ribs and the inclined surfaces thereof increasing progressively in height from the inlet toward the connection, thereby forming a combined atomizing means and fuel-directing ramp. 35
